Primary Examiner — Kevin Rudzinski(74) *Attorney, Agent, or Firm* — King & Spalding LLP(57) **CLAIM**

The ornamental design for a light module, as shown and described.

DESCRIPTION

FIG. 1 is a bottom perspective view of a light module, showing my new design;

FIG. 2 is a bottom plan view thereof;

FIG. 3 is a top plan view thereof;

FIG. 4 is a top perspective view thereof;

FIG. 5 is a front elevation view thereof;

FIG. 6 is a right-side elevation view thereof;

FIG. 7 is a back elevation view thereof; and,

FIG. 8 is a left-side elevation view thereof.

In the drawings, the dash-dot-dash broken lines indicate the boundaries of the claim while the evenly spaced broken lines depict unclaimed environment. The broken lines form no part of the claimed design.
